UNITED STATES PATENT OFFICE.

DAVID J. STARRETT, OF THOMASTON, MAINE, ASSIGNOR OF ONE-HALF TO
JOHN RUGGLES, OF CAMBRIDGEPORT, MASSACHUSETTS.

PAINT-MIXER.

SPECIFICATION forming part of Letters Patent No. 314,546, dated March 24, 1885.

Application filed March 18, 1884. (No model.)

To all whom it may concern:

Be it known that I, DAVID J. STARRETT, of 5
Thomaston, in the county of Knox and State
of Maine, have invented a new and useful Im-
provement in Paint-Mixers; and I do hereby
declare that the following is a full, clear, and
exact description of the same.

My invention relates to the mixing of paints;
and it consists of a suitable receptacle adapted
10 to receive the materials, provided with a wire
mesh or its equivalent extending across the
middle thereof, the receptacle being suitably
supported upon standards, so as to be given a
rotary motion, whereby the materials are thor-
15oughly mixed and cut up by passing through
the wire mesh, and, further, in the details of
construction.

In the accompanying drawings I have re-
20 presented one form of receptacle with my im-
provements embodied, Figure 1 being a cen-
tral vertical section; Fig. 2, a vertical central
section a quarter-turn from Fig. 1, and Fig.
3 is a horizontal section taken above the wire.

In the drawings I have represented at A a
25 suitable stand for supporting the receptacle
containing the material. This consists of a base
and two uprights slotted at their upper ends
to receive the trunnions a a on the side of the
paint-receptacle B, by which the receptacle is
30 suspended, and upon which it is capable of
being given a rotary motion. The receptacle
may be of any desired size and shape, though I
prefer the form shown. Through the center
35 of the receptacle I run wires parallel to each
other in two directions, as shown; or they may
be run in any way so as to form a wire mesh
of the desired fineness, this depending some-
what upon the degree of fineness to which it
40 is desired to bring the paint. These wires
are preferably secured by being run in and
out through holes bored in the receptacle; but
any other means of attachment—such as to
staples within the receptacle—may be used.

I form the receptacle with an opening, b,
45 in the top for the admission of the material,
and a plug or cover, c, with beveled edge, is
adapted to fit snugly therein and effectually
close the same.

In order to hold the cover in securely against
50 the centrifugal force during the revolution of
the receptacle, and against the pressure of
the paint inside, I provide two rings, d d,
connected to the receptacle near the top by

straps e e, so that the said rings project a
little above the top thereof. I then place a 55
strip, f, of stout wood or metal across the top
of the barrel, resting upon the chines thereof
and held by the rings, the ends of the strip
projecting far enough for this purpose.

Between the strip f and the cover c, I place 60
a wedge, g, and drive it in to securely hold
the cover in position. This is a very con-
venient form of holding device, and I prefer
it; but of course any other device or arrange-
ment may be used with equally good effect, 65
and I do not limit myself in this respect. I
also provide the top of the receptacle with a
small opening, h, and a screw-plug, i, so that
the state of the mixture can be ascertained
without removing the cover. 70

The paint or other liquid or semi-liquid
material is put into the receptacle with any
ingredients which are to be incorporated there-
with, the cover put on and secured in place,
and then the receptacle is rapidly revolved, 75
the paint, &c., being thrown from one end to
the other and thoroughly cut up and mixed in
its passage through the wire mesh in the cen-
ter of the receptacle.

I do not limit myself to the specific ar-
rangement of the wires or their exact loca-
tion, as they may be placed lengthwise of the
barrel with the same results, or diagonally of
the same. 80

What I claim as my invention, and desire to 85
secure by Letters Patent, is—

1. In a paint-mixer, a receptacle to con-
tain the paint, a wire mesh extending across
the interior of the same and secured to the
walls thereof, the receptacle being so arranged
90 as to be capable of rotary motion, whereby
the paint is thoroughly mixed and cut up by
passage through the said wire mesh, substan-
tially as described.

2. In a paint-mixer, and in combination, the
95 wire mesh adapted to cut and mix the paint,
the cover c, loops and rings d d, strip f, and
wedge g, all arranged substantially as de-
scribed.

In testimony whereof I have signed my name 10
to this specification in the presence of two sub-
scribing witnesses.

DAVID J. STARRETT.
